UNITED STATES PATENT OFFICE

JOSEPH ARTHUR BOLDUC, OF MONTREAL, QUEBEC, CANADA, ASSIGNOR TO AUTOMOBILE "LOCK-ALARM" CORPORATION, OF NEW YORK, N. Y., A CORPORATION OF NEW YORK

ALARM APPARATUS

Application filed January 11, 1926. Serial No. 80,403.

This invention relates to alarm apparatus, and more particularly to an apparatus which is primarily intended for application to motor vehicles for the purpose of apprising the owner and others that an attempt is being made by an unauthorized person to operate the vehicle.

It is the primary object and purpose of my present improvements to simplify and materially increase the reliability and efficient operation of such an apparatus as is shown for instance in my pending application for patent Serial No. 58,349, filed September 24, 1925.

The essential characteristics of the invention may be briefly referred to as comprising a primary electrical circuit in which a make and break device and a manually operable switch are included and an alarm operating circuit connected in the primary circuit and having one or more concealed switches interposed therein which when momentarily closed will cause the operation of the alarm, and said circuit also including means whereby the sounding of the alarm will continue even though the switch be again opened.

It is one of the important objects of the invention to provide a single manually operable part for operating the make and break device in the primary circuit to open the same, said part forming a part of the alarm operating circuit and coacting with key controlled means to cause a break in said circuit. This key actuated means is so constructed and arranged that it is not necessary to employ the key for closing the alarm operating circuit, the use of the key being required only in order to release manually operable part for the purpose of opening the alarm circuit and closing the break in the primary circuit.

It is another important object of the invention to provide a making and breaking device for the alarm circuit as above referred to which is so constructed, mounted and arranged that after it has once been operated by the push button or other manually operated part to close the circuit, it is impossible to open said circuit to stop the operation of the alarm without the use of the proper key.

I may also provide an additional switch

for closing the alarm circuit operated upon the insertion of the key to open the alarm circuit whereby said alarm device will be momentarily operated prior to opening of its circuit, thus warning the owner, even though the proper key be used, that an attempt at theft of the vehicle is being made.

With the above and other objects in view, the invention consists in the improved alarm apparatus, and in the form, construction and relative arrangement of its several parts as will be hereinafter more fully described, illustrated in the accompanying drawings, and subsequently incorporated in the subjoined claims.

In the drawings, wherein I have disclosed one simple and practical embodiment of the invention, and in which similar reference characters designate corresponding parts throughout the several views,

Figure 1 is an elevation, the housing or casing for the several parts being shown in section and the mechanism illustrated in proper condition to sound the alarm upon closing of the switch;

Fig. 2 is a horizontal sectional view taken substantially on the line 2—2 of Fig. 1;

Fig. 3 is a view similar to Fig. 1 and showing the relative positions of the parts with the alarm circuit closed;

Fig. 4 is a sectional view taken substantially on the line 4—4 of Fig. 3;

Fig. 5 is a horizontal section taken on the line 5—5 of Fig. 3;

Fig. 6 is a similar section taken on the line 6—6 of Fig. 3;

Fig. 7 is an enlarged detail section of the make and break device for the alarm circuit;

Fig. 8 is an elevation of a part of the dashboard of the vehicle illustrating the arrangement of the apparatus thereon;

Fig. 9 is a diagrammatic view showing the normal condition when the vehicle is being operated by the owner with the primary or ignition circuit closed, and

Figs. 10 and 11 are detail views of the key actuated switch device for closing the alarm circuit.

Referring in detail to the drawings, wherein I have illustrated the several essential

parts of the apparatus enclosed within a suitable casing or housing 3 which is adapted to be mounted on the underside of the vehicle dashboard indicated at D in Fig. 8 of the drawings, as shown more particularly in Fig. 9 thereof, the wires or other conductors 1 and 2 respectively, may be connected in any suitable manner with a plurality of suitable switches connected with various parts of the vehicle, as for instance, the engine hood, doors, brakes or spare tire lock, so that when any attempt is made to disturb the normal condition of the parts the switch will be closed.

15 Suitably mounted in one wall of the box 3 and insulated therefrom the spaced binding posts 4, 5, 6 and 7 respectively, are arranged. A conductor 8 extends from the post 4 to the ignition apparatus of the vehicle and is subsequently grounded. A conductor 9 is connected to the post 5 and to the battery 10 and thence to the ground. This conductor 9 has interposed therein the ignition switch indicated at 11 and to said conductor at opposite sides of the switch 11, the lines 1 and 2 are joined.

30 An audible signalling or alarm device such as an electrically operated horn 12 is connected to the binding post 6 and to the ground as at 13. A conductor 14 extending from the post 7 is joined to the conductor 9 between the battery 10 and the ignition switch 11.

35 Upon the plate 15 suitably secured to the base wall of the box 3 an electromagnet 16 is mounted. A bracket 17 is also fixed to the box wall and is provided with an angularly disposed apertured guide lug 18 which slidably guides a manually operable part 19 extending through an opening 20 in one side wall of the casing or housing 3. The outer end of this part 19 has bearing contact against the short arm 21 of an L-shaped lever 22 which is pivoted as at 23. The other arm of this lever is engaged by the inner end of a 40 push button 24 suitably mounted in an opening in the dashboard D of the vehicle.

Within the casing or housing 3 spaced plates 25 and 26 respectively, are pivotally mounted for swinging movement and are 45 yieldingly urged in one direction by the springs 27. A similar plate 28 is also pivotally mounted between the plates 25 and 26 and carries a rod or bar 29 engaged with one side of the plates 25 and 26 to swing the latter against the action of the springs 27. The plate 25 adjacent one edge is provided with a shoulder 30 for a purpose which will be later pointed out, while the plate 26 is 50 formed at its free end with an arm or extension 31 having a sheet of insulating material 32 secured upon one side thereof. This arm is adapted for engagement in a notch or recess 34 formed in an upstanding flange 33 on the part 19 so that the shoulders in the op-

posite ends of this recess will engage the edges of the metal arm 31.

To the binding post 4 a resiliently yieldable conductor bar 35 is connected and is provided with a contact 36 adapted to engage a similar contact 37 on a rigid conductor plate 38 connected with the binding post 5. As will be later described, the part 19 has its end opposed to an insulating block 39 on the conductor element 35 and is adapted to move said conductor and break the connection between the contacts 36 and 37 whereby the ignition circuit will be opened independently of the switch 11.

Spaced binding posts 40 and 41 are mounted on the plate 15, the post 40 having a connection 42 with the conductor 38 and a connection 43 with the winding of the electromagnet 16. The post 41 is connected by a wire 44 with the hinged or pivoted plate 26. In a suitable bracket 45 insulated from the plate 15 an adjustable screw or pin 46 is mounted for engagement by a resilient metal strip 47 to which an armature 48 is fixed at one of its ends, the other end of said armature being provided with a contact pin 49 insulated therefrom and connected by conductor 50 with the binding post 6. The remaining binding post 7 is connected by conductor 51 with a contact 52 opposed to the contact 49.

The part 19 is normally urged in one direction to a normal position by a coil spring 53, in which position of said parts, contacts 36 and 37 are engaged for closing the ignition circuit. For the purpose of operating the plates 25 and 26 to permit the return of said part to its normal position and the breaking of the alarm circuit at the contacts 49 and 52, I provide a pin tumbler lock 54 of any conventional type suitably mounted in the dashboard D of the vehicle and having its barrel connected by a rod 55 with the intermediate pivoted or hinged plate 28. Thus, it will be apparent that upon the insertion of the proper key and the rotation of the lock barrel the plates 25 and 26 may be moved with respect to the part 19 so as to disengage shoulder 30 from the end of the armature and the arm 31 of plate 26 from the notch 34 of the part 19.

As shown in Figs. 10 and 11 of the drawings, I may provide an additional switch connected in the lines 1 and 2 and closed by the lock key 56 so as to momentarily close the alarm circuit when the key is inserted and before rotating the lock barrel. As shown, this switch may consist of opposed fixed and movable contacts 57 and 58 respectively, the contact 58 being resiliently held in a normal open position and provided with a pin or stud 59 movable through an opening in the wall of the lock case and normally projecting into the key passage of the lock barrel. Thus, this pin or stud will lock the

barrel against any attempt to turn the same without using the proper key. The two switch parts 57 and 58 are connected by means of suitable conductors 60 and 61 respectively, with lines 1 and 2. Thus, when the proper key 56 is inserted, the pin 59 will be forced outwardly, thereby engaging contact 58 with the contact 57 and closing the circuit so that the alarm device 12 will be sounded in a manner which I shall now explain.

In the normal operation of the vehicle equipped with my new alarm apparatus, the parts are in the relative positions shown in Fig. 9 of the drawings, with the contacts 36 and 37 engaged with each other while the insulation 32 on the arm 31 of the hinge plate 26 is engaged with the part 19. Thus, when the ignition switch 11 is closed in the usual way, the current flows from battery 10 through conductor 9 to the post 5 and along the conductor 38 through contacts 36 and 37 and conductor bar 35 and post 4 and hence through conductor 8 to the ignition apparatus and from the latter to the ground.

When the owner or operator of the vehicle leaves the same unattended, he merely pushes upon the button 24, and thereby rocks lever 22 to force the part 19 inwardly. The end of this part bearing against the lug 39 disengages contact 36 from the contact 37 and thereby breaks the ignition circuit independently of the switch 11. At the same time, the notch 34 in the flange 33 of said part 19 moves beneath the arm 31 of plate 26 and this arm is urged downwardly into said notch by the spring 27 so that the opposite end edges of the notch are engaged with the side edges of said arm. The parts are now in the position shown in Fig. 1 of the drawings. Should the ignition switch 11 now be closed in the attempt by one contemplating the theft of the machine to operate the same, the current will flow from the battery along the conductor 9 to the post 5 and the conductor 38 to the post 40 through conductor 43 and the windings of the magnet 16 to the screw 46 along the strip 47 to the post 41, thence along conductor 44 to plate 26 through part 19 to bracket 17 and the wall of the casing or housing to the ground. Thus a circuit energizing the magnet 16 is completed whereupon the armature 48 is attracted to engage contact 49 with contact 52, the armature being locked in such position by plate 25, the shoulder 30 of which drops behind the end of the armature. This condition of the parts is shown in Fig. 3 of the drawings, and in such movement thereof strip 47 is disengaged from the screw or pin 46 and the current from the battery now flows through conductor 14, post 7, conductor 51, contacts 52 and 49 and conductor 50 to post 6 and hence to the grounded horn 12 or other sounding device.

It will be observed that such circuit is entirely independent of the ignition switch 11

so that if this switch be again opened, the horn will nevertheless, continue to sound. The same condition will obtain in the event that any one of the other switches interposed in the lines 1 and 2 is opened and then subsequently closed. In order to stop the operation of the alarm, the proper key is inserted in the lock and the lock barrel given a half turn, thereby disengaging parts or latching devices 25 and 26 from the armature 48 and part 19 respectively. The spring 53 thereupon retracts and returns said part to its normal position while the contact 36 again engages the contact 37 to close the ignition circuit. Before withdrawing the key, the rotation of the lock barrel is reversed, thus permitting the springs 27 to act upon plates 25 and 26 until the insulation 32 of the latter plate engages upon the part 19.

From the foregoing, it will be seen that I have materially improved the apparatus shown in my former application and have eliminated the necessity of using the key in order to place the parts in condition to close the alarm circuit, such operation being instantly performed merely by the pressure of the finger upon the push button 24. Since I mount the entire apparatus upon the under side of the dashboard, it is entirely inaccessible and by ingeniously concealing the various switches, it becomes practically impossible for one contemplating theft of the vehicle to accomplish his purpose without operation of the audible signalling device. While I have particularly referred to the alarm apparatus as intended for use in connection with motor vehicles, it is possible that the essential features of the invention might also be advantageously employed in various other connections and for different purposes. Accordingly, it is to be understood that I reserve the privilege of adapting the device to such other uses and also the right of incorporating the novel features thereof in various other alternative structures and adopting all such legitimate modifications in the form, construction and relative arrangement of the several parts as may be fairly embodied within the spirit and scope of the invention as claimed.

I claim:

1. An alarm device for motor vehicles comprising a circuit including a source of current, a normally open manually operable switch, a normally closed switch carrying an armature, a magnet adjacent the last-named switch to be energized upon closing the circuit to attract said armature and open the latter switch, a second normally open switch in the circuit connected with the first-named switch and including a part supported for rectilinear sliding movement, a second circuit including an alarm and the source of current and a circuit closer engageable by the armature to be moved to closed position upon energization of the magnet, an ignition circuit including the

source of current, the first-named switch, and a second normally closed switch having a member to be engaged by said slidable part and actuated to open position by movement of said slidable part in the first circuit to its closed position, manually operable means co-acting with said slidable part to move the same to circuit closing position, locking parts to hold said slidable part, and means to withdraw the locking parts to release said slidable part for movement back to open position.

2. An alarm device for motor vehicles comprising a circuit including a source of current, a normally open manually operable switch, a normally closed switch carrying an armature, a magnet adjacent the last-named switch to be energized upon closing the circuit to attract said armature and open the latter switch, a second normally open switch in the circuit connected with the first-named switch and including a part supported for rectilinear sliding movement, a second circuit including an alarm and the source of current and a circuit closer engageable by the armature to be moved to closed position upon energization of the magnet, an ignition circuit including the source of current, the first-named switch, and a second normally closed switch having a member to be engaged by said slidable part and actuated to open position by movement of said slidable part in the first circuit to its closed position, a pivoted lever having an arm engaging one end of said slidable part, and a manually operable push button engaging a part of said lever to actuate the same and move said part to its circuit closing position, locking parts to hold said slidable part, and means to withdraw the locking parts to release said sliding part for movement back to open position.

3. An alarm device for motor vehicles comprising a circuit including a source of current, a normally open manually operable switch, a normally closed switch carrying an armature, a magnet adjacent the last-named switch to be energized upon closing the circuit to attract the armature and open the latter switch, a second normally open switch in the circuit connected with the first-named switch and including a conductor supported for rectilinear sliding movement, and a spring yieldingly holding the conductor in its open circuit position, push button operated means for moving said conductor to its circuit closing position, a second circuit including an alarm and the source of current and a circuit closer engageable by the armature to be moved to closed position upon energization of the magnet, an ignition circuit including the source of current, the first-named switch and a second normally closed switch having a movable element, one end of said conductor being directly engaged with the movable element of said switch to move the same to open position when the conductor is moved to its circuit closing position.

sition, latching devices for maintaining the conductor in said position, and means for releasing the latching means so that the slidable conductor can be moved back to open position.

4. An alarm device for motor vehicles comprising a circuit including a source of current, a normally open manually operable switch, a normally closed switch carrying an armature, a magnet adjacent the last-named switch to be energized upon closing the circuit to attract the armature and open the latter switch, a second normally open switch in the circuit connected with the first-named switch and including a conductor supported for rectilinear sliding movement, and a spring yieldingly holding the conductor in its open circuit position, push button operated means for moving said conductor to its circuit closing position, a second circuit including an alarm and the source of current and a circuit closer engageable by the armature to be moved to closed position upon the energization of the magnet, an ignition circuit including the source of current, the first-named switch and a second normally closed switch having a movable element, one end of said conductor being directly engaged with the movable element of said switch to move the same to open position when the conductor is moved to its circuit closing position, latching devices for maintaining the conductor in closed position, and a key-actuated lock operatively connected with said latching devices to move the same to their released positions and permit the slidable conductor to return to its open position.

In testimony that I claim the foregoing as my invention, I have signed my name hereto.

JOSEPH ARTHUR BOLDUC.
